GROUND ROD CONSTRUCTION

Andrew A. Hocher, Glenshaw, and Richard G. Robbins, Pittsburgh, Pa., assignors to Hubbard and Company, a corporation of Pennsylvania

Application December 9, 1947, Serial No. 790,632

4 Claims. (Cl. 174—7)

1

This invention pertains to rod structure for electrical grounding purposes, and particularly, to improved connector arrangements therefor. One phase of my invention deals with procedure for making and assembling an improved form of ground rod.

Ground rods are employed with various types of electrical equipment and have a wide field of application in connection with electric transmission lines and systems. Since it is customary to connect non-ferrous electric current conductors (cables or wires) to the ground rod, factors of corrosion, of obtaining and maintaining a good electrical contact, of avoiding galvanic action, etc., must be considered along with questions of mechanical strength, cost, simplicity of construction, etc.

Galvanic and corrosive action are accentuated, since the ground rod and its connections are ordinarily exposed to moisture and outside atmospheric conditions. As a result, it has been customary to employ connections and rods both of which are of a non-ferrous metal such as copper or copper weld (clad) steel. However, a non-ferrous metal is much more expensive, and has less mechanical strength than a ferrous metal. This latter characteristic of a non-ferrous metal is particularly disadvantageous, since the ground rod is ordinarily driven with a sledge into the ground for a sufficient distance to provide an all-weather electrical connection with moist portions of the soil.

Since ordinary steel and iron (ferrous metal) rods are subject to rusting, it is advantageous to galvanize them with zinc or some other suitable metal to provide them with a protective surface. However, those skilled in the art have felt that the disadvantageous effects of galvanic action are further augmented when an electrical connection is made from a non-ferrous connector to a galvanized rod. As a result, the industry does not favor the use of ferrous rods and has built up a definite resistance against their employment.

As will be appreciated, a good electric connection must be at all times maintained between the non-ferrous electrical conductor, the connection and the ground rod if the ground rod installation is to serve its purpose. Rusting or corrosion between conducting surfaces produces a metallic oxide and galvanic action also produces various metal compounds which hinder the efficient transmission of an electric current.

We have made the discovery that a galvanized ferrous metal rod can be successfully employed, and by reason of this discovery have been able to

5 open up an entirely new field of ground rod utilization. Briefly, we have discovered that a galvanized rod may be successfully employed without setting up objectionable galvanic or other type of corrosive action, particularly adjacent ferrous and non-ferrous conducting surfaces, provided that such surfaces make a pure metal-to-metal contact and are protected by the nature of the construction, and also, provided that transmission of electrical current between a non-ferrous connector and a ground rod is not dependent on an interposed galvanized surface.

10 Homogeneity is a promoter of high corrosion resistance and one method of making certain of 15 homogeneity is to use a pure base metal with no foreign material which can separate from the parent mass.

15 From the electromotive series (25° C.), it appears that copper has a positive potential of about 20 0.344, iron has a negative potential of about 0.441, and zinc has a negative potential of about 0.762. It will thus appear that zinc has almost twice as much of a negative potential as iron. This is one of the reasons that we wish to avoid 25 dependence upon the electrical conductivity of a contact between a galvanized coating and a non-ferrous connector to which an electrical conductor is to be connected or clamped.

30 We also believe that galvanic action between two electric-current-conducting surfaces of unlike metals such as iron which is ordinarily anodic and copper which is ordinarily cathodic, will be increased by the interpositioning of another metal of higher potential therebetween, for example, 35 zinc which is ordinarily anodic. That is, it is felt that a sacrificial corrosion of the zinc is effected. A mass of corrosion product abnormal to the composition of a base metal provides a very poor electrical contact.

40 Iron, itself, tends to corrode in the presence of oxygen to produce ferrous and ferric hydroxides which are too coarse to be efficiently protective of the parent metal. A metal such as zinc or a suitable zinc alloy is anodic to iron and the iron is cathodic to the zinc in the sense that it is 45 protected thereby. Zinc not only protects the underlying or ferrous base metal, but also by virtue of its chemical nature, definitely protects the iron where it is exposed by small imperfections or fractures in the coating. Thus, we have 50 determined that in the manufacture of a ground rod structure, we can obtain good protection of the ferrous base metal by the employment of a galvanized coating, even where as set forth in a modified embodiment of our invention, we may 55

leave a small hair-like or fine line of exposure of the base metal adjacent to a non-ferrous connector. That is, we have been able to provide a demarkation between a galvanized coating of a ferrous base metal and a non-ferrous connector which is mounted on the base metal portion of the ground rod, without providing an actual direct contact between the galvanized surface and the non-ferrous connector.

We have for the first time provided a practical type of connection between a ferrous ground rod and a non-ferrous ground rod connector and have done so without the use of a complex, involved, or expensive fabricating or assembling procedure. In accordance with our invention, we have been able to obtain a pure metal-to-metal, current-carrying contact between conducting surfaces of different base metal composition under conditions such that these surfaces are in effect embedded and protected from atmospheric conditions, the interpositioning of a third metal between these surfaces is eliminated, and exposed surfaces have the maximum possible resistance to corrosive and galvanic action under atmospheric conditions. Since current will normally follow the path of least resistance, it will be apparent that electric current flow between the ground and a conductor is substantially concentrated or centralized along a path representing these surfaces. This not only increases the efficiency of current conduction, but also minimizes galvanic action between other or exposed metal surfaces.

That is, in accordance with our invention, electric current is conducted through what may be termed inner, closed-off or protected surface or wall portions of the ground rod and the connector without reliance upon conducting properties of an adjustable clamping means (e. g. a bolt or nut) that is employed to secure the electrical conductor to the connector or its flange. We have been able to provide a substantially integral structural arrangement of highly electrically-conductive nature between a ground rod and a conductor connector, have been able to eliminate sliding clamp connections with their inherent inefficiency, and to eliminate welded joints.

A welded type of joint is disadvantageous in the first place in that considerable difficulty is encountered in properly welding ferrous and non-ferrous parts of different melting points, and the homogeneity of the metals is upset at the line of weld. There is always the question whether to use an alloy weld metal, or a weld metal representing one of the parts to be joined. Some scale or metal oxide tends to get into the weld due to the action of oxygen on molten metal, thus decreasing the electrical-conducting efficiency of the weld; welding flux also tends to lower its conductivity. It will thus appear that a weld joint is not the solution to the problem, since such joint, apart from its poor conducting properties, is somewhat porous and subject to corrosive and galvanic action.

In accordance with a preferred method of our invention, ground rods are fabricated from ordinary rod stock by a simple up-set forging operation. The rod is then punched out to leave a bore hole therein and can be galvanized by any suitable method. Ordinarily a hot dip procedure is preferred, since any desired thickness of coating may be provided, and such a coating is relatively uniform and has an alloyed interface with the base metal.

After the galvanizing operation, we then tap the bore hole to remove the galvanized coating and the alloy interface, if there is one, to thus expose the base metal of the ground rod within the wall of the bore. In accordance with a modified procedure, we also grind off or otherwise remove the galvanized coating and any alloy interfacing on one or both sides of the rod about the bore hole to a diameter or to an area extent slightly larger than a corresponding diameter or area extent of a flange portion of the non-ferrous connector which is to be mounted in the bore of the ground rod. This flange, as will be appreciated, when in position against one side of the connector mount face of the ground rod, is in direct abutment with the base metal of the ground rod, and has a fine line of separation at its surface or outer periphery with respect to the galvanized coating of the ground rod.

The connector may comprise one or more parts, and we prefer to have the primary part in a permanently mounted relationship within the bore hole, so that it has a substantially pure metal-to-metal contact therealong and provides a maximum surface contact. Such primary part of the connector is also preferably flanged over at its opposite ends, and at at least one end thereof, to seal off the surface portions of such connector part that closely abut adjacent surfaces of the base metal wall of the bore of the ground rod. One flange also serves as a clamping flange against which an electrical conductor may be secured by adjustable clamping means.

Although it is believed that our invention solves a definite problem in the art, in that it makes possible the practical utilization of a ferrous ground rod, as distinguished from a non-ferrous ground rod, the form of connection between the ground rod and the conductor is also new in itself and is advantageous in connection with any type of ground rod, such as a non-ferrous copper or copper-weld rod. If a copper-weld rod is employed, the threaded bore may expose the copper coating or the ferrous metal core, in that the problem of three unlike metals is not involved.

It has thus been an object of our invention to discover and evaluate the factors which have, heretofore, limited the utilization of ferrous ground rods and to provide a practical solution for the problem presented thereby;

Another object of our invention has been to provide new and improved procedure for making ground rods and/or for mounting an electrical connector on a ground rod;

A further object of our invention has been to devise a new and improved form of ground rod structure or construction;

A still further object of our invention has been to provide a less expensive, highly electrically-efficient, wear-resistant, and simplified form of ground rod construction.

These and many other objects of our invention will appear to those skilled in the art from the description, the illustrated embodiments and the appended claims.

In the drawings:

Figure 1 is a front view in elevation of a rod constructed in accordance with our invention;

Figure 2 is a fragmental side view in partial section of the rod of Figure 1;

Figure 3 is a fragmental side view in elevation and partial section, showing a form of complete

ground rod structure in an assembled relationship as constructed in accordance with our invention and embodying the form of ground rod shown particularly in Figures 1 and 2;

Figure 4 is a detail of a clamping element taken in the direction of line IV—IV of Figure 3;

Figure 5 is a reduced front fragmental view illustrating a modified type of ground rod constructed in accordance with our invention; Figure 5A is a view similar to Figure 2, as applied to the ground rod of Figure 5;

Figure 6 is a side sectional view in elevation, taken longitudinally along a connector part or sleeve-like stem element that may be utilized with the ground rod of Figure 5A;

Figure 7 is a side fragmental view in partial section showing how the connector part of Figure 6 may be assembled within the rod of Figure 5A;

Figure 8 is a view similar to Figure 3, but shows a complete assembly employing the structure of Figure 7;

Figure 9 is a side view and Figure 10 is an end view of a modified form of clamping bolt that may be employed with an assembly such as shown in Figure 7;

Figure 11 is a view somewhat similar to Figure 8, but illustrates a modified form of connector sleeve part, the utilization of the clamping bolt of Figures 9 and 10, and the utilization of a ground rod shape similar to Figure 1;

In Figures 1 to 11, inclusive, we have illustrated preferred procedure for making ground rod structures in accordance with our invention; and, in Figures 12 to 17, inclusive, we have shown a slightly modified procedure as applied to the structural embodiments of Figures 3, 7, and 11.

More specifically, Figures 12, 13, and 14 correspond somewhat to Figures 1, 2, and 3; Figures 15 and 16 correspond somewhat to Figures 5 and 7; and, Figure 17 corresponds somewhat to Figure 11, with the connector bolt removed.

In practicing our invention, we first fabricate a ground rod part of ferrous metal by any suitable method such as a forging method and provide it with a driving-down head portion, a connector mount or flattened portion, and a pointed or driving end portion. After a bore hole has been provided in the connector mount to give it an eye by any suitable method, such as punching, cutting, or drilling, the rod thus formed is then hot dipped, electrolytically treated, or by suitable conventional procedure is provided with a galvanized coating of a metal, such as zinc or a zinc alloy. In accordance with this procedure, walls of the bore of the connector mount portion of the rod are then tapped or threaded out in such a manner as to expose the ferrous base metal of the rod.

The connector of our structure is fabricated and is inserted to extend within the bore of the mount portion of the rod and is securely mounted therein in such a manner that its major surfaces are in a direct, somewhat compressed contact or tight abutment with the pure metal bore surfaces or walls of the ground rod.

In accordance with one structural embodiment of our invention, the connector comprises a primary sleeve-like stem part which is inserted within the bore of the rod, and a secondary stem or bolt which is inserted in the primary stem and is adapted to be adjusted with respect thereto to clamp an electrical conductor thereagainst. In accordance with another and preferred embodiment of our invention, a bolt-like connector stem part, itself, is mounted within and in an efficient,

electrically-conductive abutment or contact with the exposed pure metal bore of the rod.

The connector and its parts are preferably of a non-ferrous metal such as copper or a copper alloy corresponding substantially in nature to the electrical conductor which is to be used. If an aluminum conductor is to be used, then it is preferably to employ an aluminum or an aluminum alloy connector which may comprise a bolt-like stem, clamping flanges and a sleeve-like stem, if the latter is used. However, it will be apparent, as far as efficient electrical conductivity is involved, that parts of the connector (other than the stem part in contact with the bore of the ground rod) may be of any suitable metal, since the conductor 21 is tightly clamped against the integral front flange of the part thereof which is secured within the bore of the ground rod.

After a connector stem part has been inserted within the bore of the ground rod, the back end thereof may then be peened-over or upset to securely lock it in position between the back flange thus formed and an integral front clamping flange thereof, see for example, the back flange 18 and the front or conductor-clamping flange 17 of the embodiment of Figure 3.

It will thus be apparent that in accordance with our invention, an inexpensive ferrous-metal galvanized ground rod may be employed which will withstand rough usage, and particularly, sledge hammer blows in driving it into the ground, and will at the same time, have an efficient electrical-conducting connection with a conductor. The connector is sealed or closed off from moisture, etc., at its principal ground-rod abutting surfaces.

Referring to the embodiments shown in the drawings, and particularly, to the preferred embodiment of Figures 1 to 3, inclusive, we have shown a metal ground rod 10 having a driving head portion 11, a driving end portion 12, and a flattened eye or connector mount portion 13. In Figure 1, line *a* indicates the location of the bore which is cut or punched out of the mount portion 13.

Figure 1 thus illustrates steps in forming the ground rod 10. Figure 2 shows the rod after such operations have been effected and its bore has been tapped or threaded, see 14. Figure 3 illustrates the provision of a non-ferrous connector 15 having a stem 16 provided with male threads 15a, an integral clamping flange 17, and an extending back end which is peened over or upset to provide a back flange 18, after its threaded stem has been fully entered within the threaded bore 14 of the mount 13. Its front and back flanges 17 and 18 are in close abutment with the front and back, galvanized metal surfaces or faces of the mount 13.

In the embodiment of our invention shown in Figure 3, the connector has a bolt-like stem element or part 16 provided with threads 15a which cooperate with threads 14 of the bore hole. A threaded clamping nut 19 and a clamping flange 20 are adjustably mounted on the front, longitudinally-extending or projecting portion of the connector to securely clamp a conductor 21 against the integral clamping flange 17. That is, the front flange 17 extends transversely of the connector 15 and is positioned in a close, sealing off abutment with the front side or face of the mount portion 13, and with the back flange 18, effectively seals off wall portions of the bore of the rod. As shown particularly in Fig-

ures 3 and 4, the non-ferrous clamping washer 20 is of somewhat rectangular shape with cut off corners and has inwardly or backwardly extending or inclined bent edges *d*, *e*, *f*, and *g* which provide a series of four, spaced, clamping, and positioning edges for the conductor 21. The clamping washer 20 thus has an octo-edge shape.

In the embodiment of our invention shown in Figures 5, 5A, 6, and 7, the ground rod 10' is provided with a shorter length driving head 11' and an intermediate connector mount portion 13' which is located adjacent the driving portion 11'. In this embodiment, the tapped bore or eye wall 14' is adapted to receive a connector or primary sleeve-like non-ferrous stem part 25 which is threaded internally at 27 and externally at 30 and is provided with an integral front flange 26. The portion 29 of the stem is introduced into the tapped bore 14' and tightly secured in such a manner that its front or clamping flange 25 closely abuts the galvanized surface or face of the mount portion of the rod 10'. The extending end of the portion 29 is then upset in such a manner, see Figure 7, as to provide a back flange 28 which abuts a corresponding, galvanized surface or face of the mount portion of the ground rod 10'. The flanges 26 and 28 thus seal or close off the base metal walls or surfaces of the bore 14' of the ground rod 10' as well as surfaces of the connector part 25 which are in close abutment therewith.

In Figure 8, we have shown the construction of Figure 7 with a secondary bolt-like connector stem part 15' which is provided with threads 15'a, in order that such part may be adjustably positioned within the inner or female threads of the primary part 25. The connector part or element 15' is provided with a clamping nut, wrench flat or clamping flange 19' which is adapted to clamp a conductor 21 against the integral front flange 26 of the primary stem part 25.

In the embodiment of our invention shown in Figures 9, 10, and 11, we have disclosed a modified form of primary connector part or non-ferrous element 25' which has a shorter length and is upset at its back end to provide a flange 28' within an outwardly offset or cut out portion *h* of the bore of the ground rod 10''. In forming the bore hole of the mount portion 13' of the ground rod, the cut out portion *h* is provided after the galvanizing operation, or as a part of the tapping operation. Although this type of ground rod structure may employ any suitable form of secondary connector part such, for example, as 15' of Figure 8, it has been shown as employing an element 36 having threads 37. As shown in Figures 9 and 10, the part 36 has a mushroom-like head 38 that extends transversely and backwardly thereof to provide clamping edge portions 39a and 39b. Such portions have inner concave conductor-receiving faces for the conductor 21. If desired, the secondary conductor part 38 may be provided with a locking nut 39 that is adjustably mounted on its back end and may be tightened into abutment with the back flange 28' of the primary part 25'.

In Figures 12 to 17, inclusive, we have employed the same numerals for structure which has been previously described in connection with Figures 1 to 16, inclusive, but have added the numeral *b* to Figures 12 to 14, inclusive, to indicate the extent of removal of the galvanized

coating 10a from a planar back face or surface of the mount portion 13 and the numeral *c* to indicate the extent of removal of the coating from a planar front face or surface of such mount portion. In the embodiment of Figures 15 and 16, the numerals *b'* and *c'* are used for the same purpose; and, in the embodiment of Figure 17, the numeral *c''* is used to indicate the extent of removal of the coating from the front face or surface of the mount 13''.

In accordance with the procedure of these latter figures, the galvanized surfaces of the ground rod mount are removed about the bore hole, as by grinding them off, to expose the ferrous base metal of the rod. The diameter or width of the coating-removing action is limited in extent to substantially correspond to the maximum diameter of flange, upset, or peened portions of a connector which is to be used therewith.

By way of illustration, it will be noted that the diameter or area extent of the face *c* corresponds substantially to the diameter or area extent of the clamping flange 17 and that the diameter or area extent of the flange head 18 corresponds substantially to the diameter or extent of the pure metal face *b*, but that there is a small line of demarcation between the edges of the coating 10a and the outer or peripheral edges of the flanges 17 and 18. That is, the galvanized coating 10a on one planar surface or face of the connector mount portion 13 of the rod terminates at the outer edge of *b* and on the other planar face or side terminates at the outer edge of *c*, see Figure 1, in such a manner that the closing or sealing off spaced-apart flanges 18 and 17 are in close adjacency to the coating 10a and in a spaced relationship from terminating edges thereof.

Although we prefer to galvanize a ferrous metal ground rod before mounting a connector thereon, the galvanizing may be effected after the connector stem has been secured within the bore or centrally positioned eye portion of the ground rod. In such a case, the galvanized coating should at least, be removed from the integral clamping flange face of the connector stem against which the conductor 21 is to be secured. In this connection see the flange 17 of Figure 1, the flange 26 of Figure 8 and the flange 26' of Figure 11.

As will be noted particularly from the illustrated embodiments of my invention shown in Figures 1 to 4, inclusive, and 12 to 14, inclusive, I have provided a metal ground rod 10 having a longitudinally-extending, rod-like, integral body whose lower pointed drive portion 12 extends longitudinally for facilitating driving it into the ground, and whose upper driving end portion 11 extends longitudinally from the upper end of its integral body and terminates in the mount portion 13 of novel design. This ground rod was devised to meet a particular problem in the art, namely to meet the need for a directly driven type of ground rod of good mechanical strength which has better corrosion resistance and electrical conducting properties. Its up-set-forged mount portion 13 that is on its integral body has a pair of radially bulged-out or rounded somewhat circular sides of greater diameter than the adjacent rod-like portions of its integral body. Such mount portion 13 also has a pair of substantially flattened or planar front and back side faces of substantially the same diameter as the adjacent portions of its rod-like integral body.

(see Figures 2 and 13). The eye portion 14 is substantially centrally positioned in its mount portion 13 and extends transversely through the front and back faces of such mount portion and exposes the base metal of the integral body along its eye wall. The non-ferrous connector stem part 15 has a front abutment flange 17 extending integrally-radially from its intermediate portion and also integral stud portions 15a and 16 extending from opposite sides of the front abutment flange 17 and provided with male threads thereon or thereabout. One stud portion 15a is permanently mounted to extend through the eye portion 14 along its eye wall in engagement with the female threads thereof and in a direct electrical contacting relation with the base metal of the rod body. A back face of the front abutment flange 17 is positioned in a close sealing-off abutment with the front side face of the mount portion 13 and the up-set, back abutment flange 18 extends integrally-radially from the end of the stud portion 15a and has a front face in close, sealing-off abutment with the back side face of the mount portion 13. The other stud portion 16 projects outwardly from the front abutment flange 17, and the clamping nut 19 is adapted to be adjustably mounted on its threads to secure the non-ferrous conductor 21 tightly against the front face of the front abutment flange 17. The clamping washer 20 is adapted to be positioned on the stud portion 16 between the flange 17 and the nut 19 and has, as shown particularly in Figure 4, the series of peripherally spaced-apart, backwardly bent edge portions d, e, f, and g which serve to guide the conductor 21, prevent it from being turned or loosened, and thus hold it in a secure position against the front face of the front abutment flange 17.

Although we have shown embodiments of our invention for the purpose of illustration, it will be apparent to those skilled in the art that various modifications, additions, and subtractions may be made to the structure and procedure shown without departing from the spirit and scope of our invention, as indicated by the appended claims.

What we claim is:

1. An improved ground rod that is adapted to be driven into the ground by blows applied to its upper end, said rod having a longitudinally-extending rod-like integral body of a base metal having good mechanical strength, a pointed drive portion at the lower end of said integral body for facilitating driving said rod into the ground, an up-set-forged mount portion on said integral body having a pair of radially bulged-out sides of greater diameter than adjacent rod-like portions of said integral body and having a pair of substantially flattened front and back side faces of substantially the same diameter as adjacent portions of said rod-like integral body, a substantially centrally positioned eye portion extending transversely through the front and back side faces of said mount portion and exposing the base metal of said integral body along its eye wall, female threads extending about and along the eye wall of said eye portion, a driving head portion at the upper end of said integral body and extending upwardly from said mount portion, a non-ferrous connector stem part, a front abutment flange extending integrally-radially from an intermediate portion of said connector stem part, integral stud portions extending from opposite sides of said front abutment flange and having male threads thereabout, one of said stud por-

tions being mounted to extend through said eye portion along its eye wall in engagement with the female threads thereof and in a direct electrical contacting relation with the base metal of said body, a back face of said front abutment flange being positioned in close sealing-off abutment with the front side face of said mount portion, an up-set back abutment flange extending integrally-radially from an end of said one stud portion and having a front face in close sealing-off abutment with the back side face of said mount portion, the other of said stud portions projecting outwardly from said front abutment flange, and a clamping nut adapted to be adjustably mounted on the threads of said other stud portion to secure a non-ferrous conductor tightly against a front face of said front abutment flange.

2. An improved ground rod that is adapted to be driven into the ground by blows applied to its upper end, said rod having a longitudinally-extending rod-like integral body of a ferrous base metal having good mechanical strength, a pointed drive portion at the lower end of said integral body for facilitating driving said rod into the ground, an up-set-forged mount portion on said integral body having a pair of radially bulged-out sides of greater diameter than adjacent rod-like portions of said integral body and having a pair of substantially flattened front and back side faces of substantially the same diameter as adjacent portions of said rod-like integral body, a substantially centrally positioned eye portion extending transversely through the front and back side faces of said mount portion and exposing the ferrous base metal of said integral body along its eye wall, female threads extending about the eye wall of said eye portion, a driving head portion at the upper end of said integral body and extending upwardly from said mount portion, a non-ferrous connector stem part, a front abutment flange extending integrally-radially from an intermediate portion of said connector stem part, integral stud portions extending from opposite sides of said front abutment flange and having male threads thereabout, one of said stud portions being mounted to extend transversely through said eye portion along its eye wall in engagement with the female threads thereof and in a direct electrical contacting relation with the base metal of said body, a back face of said front abutment flange being positioned in close sealing-off abutment with the front side face of said mount portion, an up-set back abutment flange extending integrally-radially from an end of said one stud portion in close sealing-off abutment with the back side face of said mount portion, the other of said stud portions projecting outwardly from said front abutment flange, a protective non-ferrous metal coating on the ferrous base metal of said integral body, and a clamping nut adapted to be adjustably mounted on the threads of said other stud portion to secure a non-ferrous conductor tightly against a front face of said front abutment flange.

3. An improved ground rod as defined in claim 2 wherein, the non-ferrous protective coating terminates closely adjacent to the back face of said front abutment flange, and the base metal of said body at said mount portion is directly exposed to abutting back and front faces of said front and back abutment flanges.

4. An improved ground rod as defined in claim 2 wherein, a clamping washer is adapted to be positioned on said other stud portion between said

front abutment flange and said clamping nut and has a series of peripherally spaced-apart backwardly bent edge portions to guide the non-ferrous conductor and hold it in a secure position against the front face of said front abutment flange. 5
